Inventor: George T. Johnson
by Charles F. Randall
Attorney

UNITED STATES PATENT OFFICE.

GEORGE T. JOHNSON, OF NEW YORK, N. Y., ASSIGNOR TO THE GEORGE T. JOHNSON COMPANY, OF BOSTON, MASSACHUSETTS, A CORPORATION OF MASSACHUSETTS.

DISPENSING FIXTURE FOR WEB MATERIAL.

Application filed November 13, 1923. Serial No. 674,483.

To all whom it may concern:

Be it known that I, GEORGE T. JOHNSON, a citizen of the United States, residing at New York, in the county of New York, State 5 of New York, have invented a certain new and useful Improvement in Dispensing Fixtures for Web Material, of which the following is a specification, reference being had therein to the accompanying drawings.

10 My present invention is in the nature of an improvement upon the dispensing fixture of United States Letters Patent to me No. 1,399,482, granted under date of Dec. 6, 1921.

The general object of the invention is to 15 provide a fixture of the type and general construction shown and described in my said Letters Patent, better adapted to the dispensing of web-material from rolls of different widths. In particular, an aim of the 20 invention is to provide a construction in which the spring-pressed movable plate or brake, which in the fixture of the Letters Patent resists the unwinding rotation of the roll, may be adjusted to suit the width of 25 roll without affecting the degree of frictional resistance to the unwinding revolution of the roll when in place within the fixture.

An illustrative embodiment of the invention is shown in the accompanying drawings, in which:—

30 Fig. 1 is a plan view of a dispensing fixture having the invention applied thereto, a portion of the movable plate or brake being broken away, and a roll of web material being indicated in dotted lines.

35 Fig. 2 is a view of the same in section on a horizontal plane, a roll being partly shown in full lines, the remainder of the roll in dotted lines.

40 Having reference to the drawings,—

The features in general of the dispensing fixture to which the invention is shown applied comprise a wall-plate 1 which is adapted to be secured to a wall or other surface; two arms 2 and 3 which are pivotally combined with said wall-plate and respectively provided at the ends thereof with roll-supporting hubs 4 and 5 adapted to fit within the hollow core 6 of the roll of web-material 45 rail 7; and a spindle 8 that is fixedly engaged with the head portion of hub 5 at 9, the free end of said spindle occupying a central hole in hub 4 in the closed condition 50 of the fixture. Hub 4 is provided with a

flange 10 in fixed relation therewith, for 55 frictional engagement with one end of roll 7, and hub 5 is provided with a spring-pressed flange 11 for frictional engagement with the other end of the said roll. As thus far referred to, the parts resemble those of the prior Letters Patent, except that wall-plate 1, the arms, and their hubs, consist of stamped or pressed sheet-metal instead of castings. This, however, is not material 60 so far as the invention is concerned. The means of locking the fixture in closed condition, forming no part of the present invention, comprises in this instance latch 14 occupying a longitudinal slot in the spindle near the free end of the latter, and adapted 65 to slide lengthwise within the said slot. The bottom of the said slot at the end of the latter toward the extremity of the spindle is sloped to constitute a cam-surface. The latch is notched in its outer edge, the notch 70 being occupied by a pin 15 projecting inward from a loose collar 16 that is slidably mounted on the spindle. A weak expanding spring 17 surrounding the spindle acts against the said collar 16 with a tendency to 75 press the collar, and consequently the latch 14, toward the extremity of spindle 8, as in Fig. 2, and hold the outer end of latch 14 in engagement with the cam-surface. By 80 this engagement the said outer end is displaced radially outward so that the hump or enlargement with which such end of the latch is formed projects radially beyond the spindle. In the closed together condition of the fixture this hump or enlargement 85 occupies a position within the hollow of hub 4, and engages with the edge of the shell of said hub around the hole that is occupied by the spindle, to lock the hub and 90 spindle together. Thereby the fixture is 95 locked in closed condition. Unlocking is effected, to permit opening of the fixture, by manual displacement of collar 16 along spindle 8 inward away from hub 4, so as to move the latch along the slot in the spindle 100 away from the cam-surface. Thereby the latch is rendered free to move radially inward toward the axis of the spindle, which enables the fixture to be opened by separating the arms. In the operation of closing the 105 fixture, the engagement between the edge of the hole in hub 4 and the hump or enlargement of the latch operates to push the latch

and collar along the spindle, compressing the spring 17, until the change in the position of the latch relative to the cam-surface leaves the latch free to be pressed radially inward, whereupon the said edge of the hole in hub 4 passes over and beyond the hump or enlargement of the latch, following which spring 17 acts to return collar 16 and the latch toward the extremity of the spindle 10 and the cam-surface projects the latch radially outward to lock the spindle-end and hub 4 to each other.

The principle of operation of a dispensing fixture of the type to which the invention 15 relates is that of retarding the unwinding action of the roll through friction developed by pressure upon the end surfaces of the roll. In the Letters Patent aforesaid, this retarding or braking action is effected 20 by means of a spring-pressed movable plate or brake similar to that shown at 11 in the present invention, which is forced inwardly against the corresponding end surface of the roll by a tension-spring surrounding 25 the spindle and confined between the outer side or face of said movable plate and the central portion of the hub corresponding to hub 5 of the present Fig. 2. The construction shown and described in such Letters Patent has the drawback that it has 30 nothing to compensate for the fact that with such arrangement of the tension-spring, acting directly against the movable plate, the extent of the endwise compression of 35 the spring, and consequently the tension of the spring, varies in proportion to the width of roll which is applied to the fixture, so that when a wide roll is put in place the resulting increased tension of the spring 40 forces the movable plate against the end of the roll more powerfully, with increased frictional resistance to the unwinding rotation of the roll upon the fixture. Thus by 45 reason of the want of provision for compensation the tension may become entirely too great in the case of a wide roll.

In the case of the illustrative embodiment of the present invention that is shown herein, a tension spring 12 is applied to the 50 left-hand end-portion of the spindle 8 between the central portion of hub 5 and a sleeve 13 fitting loosely upon the spindle 8. A shoulder 81 upon the spindle 8 at the inner end of the sleeve limits the extent of 55 the endwise movement of the sleeve produced by the tendency of the spring to expand. The exterior of the sleeve 13 is provided with screw-threads and the movable plate or brake 11 has an integrally formed hub- 60 portion 110 which is correspondingly threaded interiorly to engage the screw-threads on the exterior of the sleeve 13. A knurled flange 130 is provided at the inner end of 65 said sleeve 13 to enable such sleeve to be easily rotated by hand. The spokes or radial

webs 111 joining the hub 110 with the exterior or peripheral portion of the movable plate 11, located in slots extending lengthwise of the hub 5, prevent rotation of the movable plate 11 about the axis of spindle 8. 70

It will be evident that through rotation of the exteriorly threaded sleeve 13 when no roll of material is on the fixture the movable plate 11 may be shifted along the axis of spindle 8 toward or from the hub 4 at the opposite side of the fixture without in any way altering the tension of spring 12. This 75 enables the plate 11 to be positioned properly to suit a wide roll without any resulting change in the spring tension. Adjustment of 80 the operative spring tension may however be effected by an initial positioning of the plate 11 so that the closing of the fixture with a roll in position will involve an outward displacement of the plate 11 proportioned to the amount of tension desired. For instance, if the movable plate or brake 11 is set initially, by rotation of the sleeve 13, to stand a given distance nearer the opposing plate 10 than the width of a particular 85 roll which it is desired to apply to the fixture, the adjustment will enable the desired extent of axially-directed pressure to be exerted on the ends of such roll to check its rotation, regardless of the width itself. 90 It will be seen, therefore, that the fixture can be adjusted to handle all widths of rolls within the limits of its capacity, with any desired degree of pressure from the movable plate or brake 11 to retard the unwinding, 95 uncontrolled by the length of the roll itself. An important feature of the present arrangement is that the same adjustment, accomplished by rotating the sleeve 13, enables 100 the pressure of the movable plate 11 against 105 any one particular roll to be varied to increase or decrease the braking effect.

An important advantage gained by the construction shown in the drawings is that the hub 110 is able to slip over the spring 110 12 in adjusting the movable plate or brake 11 outwardly along the sleeve 13 to receive a wide roll. Thus the range of different widths of rolls accommodated by any particular fixture is increased over the prior 115 type without sacrifice of the compactness of the fixture; whereas in the prior type the presence of the tension spring between the movable plate or brake and the adjacent side-arm of the fixture reduced the extent 120 of the outward movement of said plate or brake.

The inner end of the sleeve 13 serves as an abutment between which and the collar 16 of the locking device the spring 17 is confined and compressed.

What is claimed as the invention is,—

1. A dispensing fixture comprising opposite side-arms provided with roll-supporting hubs, a spindle, and a non-rotatable 120 130

plate adapted to be pressed against the end of a roll to retard rotation, and having a plate-carrier constituted by a sleeve slidably mounted on the said spindle and upon which the said plate is mounted with capacity for adjustment axially of said sleeve, and a tension spring pressing the sleeve inwardly to bear the plate against the roll-end.

2. A dispensing fixture comprising side-arms, a spindle, and roll-supporting means adapted to receive a roll of the material to be dispensed, and having an exteriorly threaded sleeve rotatable upon said spindle, a spring pressing said sleeve inwardly along said spindle, and a brake adapted to contact with the end of the roll of material in screw-threaded engagement with the said exteriorly threaded sleeve, and adjustable

axially of the spindle through rotation of the sleeve.

3. A dispensing fixture comprising opposite side-arms, roll-supporting means, a spindle, a plate-carrier constituted by a sleeve slidably mounted on the said spindle, a tension-spring mounted upon the spindle at the outer end of said sleeve, and a non-rotatable plate adapted to be pressed through the action of the said spring against the end of a roll to retard rotation, said plate having a hub fitted to the exterior of the sleeve, adjustable along the latter, and adapted to extend outward beyond the outer end of the sleeve, encircling the said tension-spring, as the plate is adjusted outward for rolls of increased width.

GEORGE T. JOHNSON.
